PHOTOELECTRIC CELL ACTUATED TRAP
THROWING MACHINE

Vergil Frank McIntire, Banning, Calif.

Application June 28, 1950, Serial No. 170,847

11 Claims. (Cl. 124—8)

1

This invention relates to trap shooting, and in particular a plurality of photo-electric cell actuated machines distributed over a trap shooting area whereby interception of a light beam actuates operating instrumentalities that throw clay pigeons or targets into the air.

The purpose of this invention is to introduce the element of surprise in trap shooting whereby a marksman sets target throwing mechanisms in action without being aware of the presence of the said mechanism.

Various types of automatic target throwing devices and machines have been provided which discharge or throw clay pigeons and the like at spaced intervals but where the operation is automatic the time interval is ascertained by the marksman. With this thought in mind this invention contemplates target throwing machines positioned at different points around a course in which the positions of the machines are changed continuously and in which the marksman is not aware of the presence or position of the machine.

The object of this invention is, therefore, to provide means for actuating target throwing machines whereby the machines are actuated by a marksman without the marksman realizing that the machine has been released or set in action.

Another object of the invention is to provide a trap throwing machine that is automatically reset after each operation.

A further object of the invention is to provide a photo-electric cell actuated trap throwing machine which is of a comparatively simple and economical construction.

With these and other objects and advantages in view the invention embodies a trap throwing machine having a throwing arm actuated by a spring with a solenoid actuated release and with the arm returned by a friction disc wherein the arm is released and the parts actuated by the interception of a light beam.

Other features and advantages of the invention will appear from the following description taken in connection with the drawings wherein:

Figure 1 is a plan view with parts broken away illustrating the throwing arm and the operating instrumentalities thereof.

Figure 2 is a cross section taken on line 2—2 of Figure 1 illustrating the friction disc for resetting the throwing arm.

Figure 3 is a vertical section through the op-

2

erating gears by which the resetting discs and trap carrying discs are actuated.

Figure 4 is a cross section taken on line 4—4 of Figure 1 showing the mounting and operating mechanism of the clay pigeon carrying disc.

Figure 5 is a detail, or an enlarged scale illustrating a method of discharging clay pigeons to throwing positions in front of the throwing arm.

Figure 6 is a detail showing a section through the clay pigeon dropping elements taken on line 6—6 of Figure 5.

Figure 7 is a detail showing a section on line 7—7 of Figure 6 illustrating the throat of the throwing arm.

Figure 8 is a section taken on line 8—8 of Figure 1 illustrating the trip release lever for releasing the throwing arm.

Figure 9 is a section taken on line 9—9 of Figure 1 showing a section through the switch actuating lever.

Figure 10 is a detail illustrating a roller positioned in the clay pigeon carrying disc for actuating a motor switch.

Figure 11 is a plan view showing a detail of a double switch actuated by a roller as illustrated in Figure 10.

Figure 12 is a plan view of the roller shown in Figure 10.

Figure 13 is a diagrammatic view illustrating the circuits of the clay pigeon throwing machine.

Figure 14 is a diagrammatic view illustrating the tract of ground with a shooting path indicated thereon and with throwing machines distributed at different points around the tract.

Figure 15 is a detail illustrating a signal light panel positioned at spaced points in the tract to indicate whether or not the tract is clear.

Referring now to the drawings wherein like reference characters denote corresponding parts the improved target throwing machine of this invention includes a throwing arm 10 pivotally mounted on a pin 11 and actuated by a spring 12, a resetting gear 13, a clay pigeon carrying disc 14 pivotally mounted on a vertically disposed shaft 15 and a plurality of actuating solenoids with suitable circuits in which the parts are positioned.

The throwing arm 10 is slidably positioned on a plate 16 and the forward side of the arm is provided with a clay pigeon receiving throat or socket 17 which is provided in an offset section 18 as illustrated in Figures 5, 6 and 7. The socket

17 is provided with a cover plate 19 having pins 20 extended downwardly which are positioned as shown in Figure 5 to engage the inner edges of clay pigeons as indicated by the numerals 21 and 22. As illustrated in Figure 6 the clay pigeons are inserted in openings 23 in the disc 14 by pressing the clay pigeons upwardly from the under surface of the disc, and the pigeons are held against a plate 24 by springs 25 and 26 and as the clay pigeons arrive in positions above openings 27 in the plate 24 the springs press the clay pigeons downwardly as shown in Figure 6 with the clay pigeons riding on springs 28. The springs 28 urge the clay pigeons into the pocket 17 of the throwing arm 10 as indicated by the dotted lines in Figure 6.

The opposite end of the throwing arm 10 is provided with a hub 29 through which the arm is pivotally mounted on the pin 11 and, as illustrated in Figure 2 the hub is provided with a bearing sleeve 30 and the sleeve extends downwardly to a boss 31 that is journaled in a bearing sleeve 32 that extends downwardly from the plate 16. A friction washer 33 is provided between the hub 29 and plate 16.

The hub 29 is also provided with a recess 34 in which a spring 35 is positioned and the spring urges the resetting gear 13 upwardly as illustrated in Figure 2, the gear being mounted on the bearing 36. The gear 13 is also provided with a hub 37 that is positioned to frictionally engage the upper surface of the hub 29 whereby with the gear held against the upper surface of the hub 29 by a solenoid 38 the throwing arm 10 will turn with the gear and with the gear actuated in a clockwise direction the long end of the throwing arm will travel from the position shown in dotted lines in Figure 1 to the position shown in full lines, in which position it is held by a latch 39, as shown in Figure 8.

The solenoid 38 is provided with a core 40 that is pivotally connected to an arm 41 by a pin 42 and the arm is pivotally mounted in a bearing 43 on a cover plate 44 by a pin 45. The end of the pin 11 extends through a sleeve 46 in a hub 47 on the plate 44 and the upper end is positioned to extend into a socket 48 of the lever 41, as shown in Figure 2.

With the parts arranged in this manner energization of the solenoid 38 draws the lever 41 downwardly forcing the pin 11 with the gear 13 thereon downward whereby the hub 37 of the gear engages the upper surface of the hub 29 so that the throwing arm is actuated to resetting position.

The gear 13 is rotated by a worm 49 on a shaft 50 extended from a motor 51 and the worm 49 also drives the clay pigeon carrying disc 14 through a pinion 52 that meshes with a gear 53 on the shaft 15.

The shaft 15 is journaled by bearings 54 and 55 in the hub 56 of the gear 53 and this gear is resiliently urged upwardly by a spring 57 that rests upon the upper end of a bushing 58 on which the disc 14 is journaled through a bearing 59. The bushing 58 is provided with a sleeve into which the shaft 15 slides upon downward movement thereof by the solenoid 61 which moves the shaft 15 and gear 53 downward when energized. The solenoid 61 is provided with a core 62 that extends through a lever 63 pivotally mounted in a bearing 64 on a bar 65 by a pin 66. The core 62 is provided with a head 67 by which the lever is drawn downwardly. In the free po-

sition the lever is urged upwardly by a spring 68 and the outer end of the lever is pivotally connected by a pin 69 to an arm 70 that is slidably held in bearings 71 and 72 and that is provided with an upwardly extended inner end 73 that engages the under surface of the disc 14, providing a brake, retaining the disc 14 in a stationary position until the solenoid 61 is energized. By this means the gear 53 turns continuously and when the device is actuated to throw pigeons a circuit is completed to the solenoid 61 which releases the brake 73 and holds the hub 56 of the gear 53 in contact with the hub of the disc 14 so that the disc is rotated to position another pair of clay pigeons over the opening 27.

The outer end of the throwing arm 10 is provided with an opening 74 in which one end of the spring 12 is positioned and the opposite end of the spring is held in an opening 75 of a switch lever 76 which is pivotally mounted on the plate 16 by a pin 77 and which is urged against the action of the spring 12 by a spring 78, one end of which is secured in an opening 79 of the switch lever and the other in an opening 80 of a support bar 81. A stop 82 on a brace 83, that connects the outer end of the bar 81 to the plate 16 is provided to hold the switch lever against the action of the spring 12.

The latch 39 that retains the throwing arm in the cocked position is provided with a beveled upper end 84 whereby upon return movement of the throwing arm 10 the latch is forced downwardly against the tension of a spring 85 which holds the latch upwardly in the position shown in Figure 8. The latch 39 is pivotally mounted by a pin 86 on the end of a lever 87 and the lever is pivotally mounted in a bearing 88 by a pin 89. The opposite end of the lever is pivotally connected by a pin 90 to a core 91 of a solenoid 92 which is positioned on the under surface of the plate 16. As the solenoid 92 is energized the end of the lever that is connected to the core of the solenoid is drawn upwardly whereby the latch 39 is drawn downwardly so that the arm 10 is released and upon release of the arm 10 the spring 12 actuates the arm with a snap movement from the position shown in full lines in Figure 1 to that shown in dotted lines wherein the arm discharges or throws clay pigeons from the machine.

In order to properly time the operation of the motor and loading solenoid the disc 14 is provided with radially disposed openings 93 in which rollers 94 are journaled on pins 95, and the rollers are positioned to engage the switch actuating rollers 96 and 97 on arms 98 and 99, respectively, as shown in Figure 11 and the arms, which are pivotally mounted in bearings 100 and 101 actuate the switches through bars 102 and 103.

As illustrated in Figure 3 the motor 51 is suspended from an upper plate 104 by a bracket 105 and the shaft 50 is mounted in hangers 106 depending from the plates 104. The worm gear 49 meshes with the gear 13 at one side and with the gear 53 through the pinions 52 and 107 on a shaft 108. The shaft is journaled in bearings 109 and 110 in the plates 104 and 16, respectively and the pinions are secured in position upon the shaft by set screws 111 and 112 in hubs 113 and 114 respectively.

The plate 104 is mounted above the plate 16 by bolts 115 with spacing sleeves 116 thereon.

The units are provided with circuits, as illustrated in Figure 13, having photo-electric cells 125 with anode tubes 126 providing reflectors and the photo-electric cells are connected to a source of

current supply through wires 127 and 128 and connected to a starting solenoid 129 for closing a switch 130 by wires 131 and 132 which extends through a timer 133.

Closing of the switch 130 sends current to the solenoid 92 through wires 134 and 135 and the solenoid 92 actuates the latch 39 to release the throwing arm so that clay pigeons or other objects are discharged from the device.

Upon release of the spring 12 with the operation 10 of the arm 10 the spring 12 draws the switch lever 76 against the contacts 136 and 137 closing the switches 138 and 139 respectively, the switch 138 completing a circuit to the cocking solenoids 38 15 and the switch 139 completing a circuit to the motor 51.

The switch 138 is connected in series with a similar three-way switch 140 with the switch 139 connected by a wire 141 and a wire 142 to a source of current supply through the wire 127 and with the switch 140 connected by a wire 143 to one side of the solenoid 38 with the opposite side of the solenoid connected by a wire 144 to the wire 128 of the current supply through a wire 145 and a combination of three-way switches 146 and 147 25 which are connected by wires 148 and 149. The switches 138 and 140 are also connected by wires 150 and 151.

The switch 139 is connected to the motor 51 by a wire 152 and from the motor, to a source of current supply by a wire 153 and through the wire 153 to one side of the source of current supply 128 by the wires 135, 145 and 148 or 149. The opposite side of the switch 139 is connected by the wires 154 and 155 through a switch 156 which is connected to the other side of the source of current supply 127 by wires 157 and 142.

Upon closing the circuit the latch 39 is actuated by the solenoid 92 to release the throwing arm 10 which is actuated by the spring 12 and with the spring 12 released the switches 138 and 139 are closed by the switch lever 76 whereby the gear 13 operating through the friction hubs 37 and 29 returns the throwing arm 10 to the full line position shown in Figure 1 and as the arm arrives in this position it contacts the switch 140 and another switch 158 whereby the circuit is broken to the solenoid 38 so that the throwing arm 10 is released from the friction surface of the hub 37 of the gear 13 and a circuit is completed through the switches 158 and 159 to the solenoid 61 which actuates the friction clutch surfaces of the hub 56 and disc 14 whereby the disc rotates until the roller 94 engages the rollers 96 and 97 to operate the switches 156 and 159 to break the circuit to the solenoid 61 and also the circuit to the motor 51.

The switch 158 is connected by a wire 142 to the side 127 of the current supply and with the switch 158 connected to the switch 159 by wires 160 and 161 a circuit may be completed through the solenoid 61 by wires 162 and 163 and to the other side 128 of the current supply through the wires 135, 145 and 142 and through one of the wires 148 or 149.

With the trap shooting machine as disclosed the switch 147 may be actuated by a button on a suitable panel to close the circuit whereby the solenoid 92 withdraws the latch 39 to release the throwing arm and the cycle of operations is started and the operation continues as described until the switch 146 is actuated by a button to close the circuit. The timer 133 is set to prevent the circuit being completed more than once in five minutes and with a plurality of machines pos-

sitioned at different points, such as the points 5 clay pigeons or other targets will fly or will be thrown across the path as a markman crosses the line of sight between a photo-electric cell 125 and an anode 126.

The trap or course is provided with a safety wall 173, with range stations positioned at various points, and with safety panels 166, 167, 168, 169, 170 and 171, positioned at spaced intervals to warn hunters if the section ahead is clear. These panels are provided with green lights 164 and red lights 165, the red lights indicating that hunters are in the section ahead and the green lights indicating that the section is clear. The panels are provided with manually actuated switches 174 and 175.

Hunters may, therefore, travel through the course with safety and as they progress through the sections thereof targets are discharged by the machines.

It will be understood that modifications may be made in the design an arrangement of the parts without departing from the spirit of the invention.

What is claimed is:

1. A trap shooting machine comprising a base, a throwing arm pivotally mounted on the base, a spring extended from one end of the throwing arm for actuating the arm for throwing projectiles, a latch for retaining the throwing arm in the cocked position, a solenoid for releasing the latch, means returning the arm to the cocked position after throwing a projectile, a disc having radially disposed projectile carrying openings therethrough positioned to drop projectiles in the path of the throwing arm with the arm in the cocked position, rollers carried by the disc and positioned between said projectile carrying openings, means positioned to be engaged by the said rollers of the disc having the projectile carrying openings therein for halting the progress of said disc upon engagement thereof with the rollers and an electric circuit for connecting the parts.

2. A trap shooting machine comprising a base, a throwing arm pivotally mounted on the base, a spring extended from one end of the throwing arm for actuating the arm for throwing projectiles, a latch for retaining the throwing arm in the cocked position, a solenoid for releasing the latch, means returning the arm to the cocked position after throwing a projectile, a disc having radially disposed projectile carrying openings therethrough positioned to drop projectiles in the path of the throwing arm with the arm in the cocked position, rollers carried by the disc and positioned between said projectile carrying openings, means positioned to be engaged by the said rollers of the disc having the projectile carrying openings therein for halting the progress of said disc upon engagement thereof with the rollers and suitable circuits and switches for supplying current to the parts.

3. A trap shooting machine comprising a base, a throwing arm pivotally mounted on the base, a spring extended from one end of the throwing arm for actuating the arm for throwing projectiles, a latch for retaining the throwing arm in the cocked position, a solenoid for releasing the latch, means returning the arm to the cocked position after throwing a projectile, a disc having radially disposed projectile carrying openings therethrough positioned to drop projectiles in the path of the throwing arm with the arm in the cocked position, rollers carried by the disc and

positioned between said projectile carrying openings, means positioned to be engaged by the said rollers of the disc having the projectile carrying openings therein for halting the progress of said disc upon engagement thereof with the rollers, suitable circuits and switches for supplying current to the parts, and a photo-electric cell positioned to close the circuit for operating the parts.

4. A trap shooting machine comprising a base, a throwing arm pivotally mounted on the base, a spring extended from one end of the throwing arm for actuating the arm for throwing projectiles, a latch for retaining the throwing arm in the cocked position, a solenoid for releasing the latch, means returning the arm to the cocked position after throwing a projectile, a disc having radially disposed projectile carrying openings therethrough positioned to drop projectiles in the path of the throwing arm with the arm in the cocked position, rollers carried by the disc and positioned between said projectile carrying openings, means positioned to be engaged by the said rollers of the disc having the projectile carrying openings therein for halting the progress of said disc upon engagement thereof with the rollers, suitable circuits and switches for supplying current to the parts, a photo-electric cell positioned to close the circuit for operating the parts, and a motor in combination with transmission elements for operating the arm returning means and projectile placing means.

5. In a trap shooting machine, the combination which comprises a base, a throwing arm pivotally mounted on the base, said arm having a projectile receiving pocket in one end thereof, a switch lever pivotally mounted on the base, a spring connecting the end of the throwing arm opposite to that in which the pocket is positioned to the switch lever, a plurality of switches, means resiliently urging the switch lever toward the said switches, a latch for retaining the throwing arm in the cocked position, a solenoid for releasing the latch, means returning the arm to the cocked position, a plurality of switches positioned to be closed by the arm as the arm arrives at the cocked position, means placing projectiles in the path of the throwing arm with the arm in the cocked position, and suitable circuits connected to the switches and operating means and connecting the parts to a source of current supply.

6. In a trap shooting machine, the combination which comprises a base, a throwing arm pivotally mounted on the base, said arm having a projectile receiving pocket in one end thereof, a switch lever pivotally mounted on the base, a spring connecting the end of the throwing arm opposite to that in which the pocket is positioned to the switch lever, a plurality of switches, means resiliently urging the switch lever toward the said switches, a latch for retaining the throwing arm in the cocked position, a solenoid for releasing the latch, means returning the arm to the cocked position, a plurality of switches positioned to be closed by the arm as the arm arrives at the cocked position, means placing projectiles in the path of the throwing arm with the arm in the cocked position, suitable circuits connected to the switches and operating means and connecting the parts to a source of current supply, and a photo-electric cell positioned in said circuits for closing the circuits to operate the device when a beam of light extended therefrom is intercepted.

7. In a trap shooting machine, the combination which comprises a base, a throwing arm having a projectile receiving pocket in one end

with a friction hub spaced from the opposite end pivotally mounted on the base through the center of said friction hub, a projectile carrying disc pivotally mounted on the base, continuously rotating gears positioned above the friction hub of the arm and projectile carrying discs, a motor for rotating the gears, clutch elements for actuating the friction hub of the arm and projectile carrying discs by the gears respectively, a latch for retaining the throwing arm in the cocked position, a spring extended from the opposite end of the throwing arm for actuating the arm to throw projectiles, a switch lever pivotally mounted on the base and connected to the opposite end of the spring extended from the throwing arm, a plurality of switches positioned to be engaged by the said switch lever, means resiliently urging the switch lever toward the switches, a plurality of switches positioned to be engaged by the throwing arm as the arm returns to the cocked position, a plurality of switches positioned to be engaged by projections on the said projectile carrying discs, circuits connecting the switches to a source of current supply and to operating instrumentalities of the parts, and a photo-electric cell included in said circuit for closing the circuit as an object passes through a light beam extended therefrom.

8. In a trap shooting machine, a base, a throwing arm pivotally mounted on a base, resilient means tending to pivot the arm in one direction for throwing projectiles, a latch for retaining the throwing arm in cocked position, a solenoid for releasing the latch, a photo-electric cell in circuit with said solenoid, means returning the arm to cocked position after throwing a projectile and means for placing projectiles in the path of the throwing arm when the arm is in cocked position and; switch means actuated by said means for placing projectiles in the path of the throwing arm for actuating cocking mechanism for said arm.

9. In a trap shooting machine, a base, a throwing arm pivotally mounted on a base, resilient means tending to pivot the arm in one direction for throwing projectiles, a latch for retaining the throwing arm in cocked position, a solenoid for releasing the latch, a photo-electric cell in circuit with said solenoid, means returning the arm to cocked position after throwing a projectile and means for placing projectiles in the path of the throwing arm when the arm is in cocked position and switch means actuated by said means for placing projectiles in the path of the throwing arm for actuating cocking mechanism for said arm and; switch means in connection with said spring for energizing said means returning said arm to cocked position after throwing projectile.

10. In a trap shooting machine, the combination which comprises a base, a throwing arm pivotally mounted on the base, said arm having a projectile receiving pocket in one end thereof, a switch lever pivotally mounted on the base, means connecting the end of the throwing arm opposite to that in which the pocket is positioned to the switch lever, a plurality of switches, means resiliently urging the switch lever toward the said switches, means for retaining the throwing arm in cocked position, a solenoid for releasing the last named means, means returning the arm to the cocked position, a plurality of switches positioned to be closed by the arm as the arm arrives at the cocked position, means placing projectiles in the path of the throwing arm with the arm in the cocked position, and suitable cir-

cuits connected to the switches and operating means and connecting the parts to a source of current supply.

11. In a trap shooting machine, a base, a throwing arm pivotally mounted on said base, means tending to pivot the arm in one direction for throwing projectiles, means for retaining said throwing arm in cocked position, a solenoid for releasing the last named means, a photo-electric cell in circuit with said solenoid, means returning the arm to cocked position after throwing a projectile, and means for placing projectiles in the path of the throwing arm when the arm is

5

in cocked position, and switch means actuated by said means for placing projectiles in the path of said throwing arm for actuating the cocking mechanism for said arm.
